UNITED STATES PATENT OFFICE.

CHARLES P. HOWE, OF GALVESTON, TEXAS.

MATTRESS-MAKING MACHINE.

SPECIFICATION forming part of Letters Patent No. 233,512, dated October 19, 1880.

Application filed March 19, 1880. (Model.)

To all whom it may concern:

Be it known that I, CHARLES P. HOWE, of Galveston, in the county of Galveston, and in the State of Texas, have invented certain new and useful Improvements in Mattress-Making Machines: and I do hereby declare that the following is a full, clear, and exact description thereof, reference being had to the accompanying drawings, and to the letters of reference 10 marked thereon, making a part of this specification.

The nature of my invention consists in the construction and arrangement of a machine for making mattresses, as will be hereinafter more 15 fully set forth.

In order to enable others skilled in the art to which my invention appertains to make and use the same, I will now proceed to describe its construction and operation, referring to the 20 annexed drawings, in which—

Figure 1 is a perspective view of my mattress-making machine, and Fig. 2 is a longitudinal vertical section of the same.

A represents the base of the machine, at one 25 end of which are two posts or standards, B B. Upon a rod, *a*, between said standards are pivoted the two side pieces, C C, which are provided with legs E, for supporting the same in about a horizontal position. At the forward 30 ends of the side pieces, C C, at the bottom, on a rod, *b*, is hung a door or gate, D, which closes upward and has grooves *e*, to receive the ends of the side pieces, said door being then held by latches *d d*.

Below the rod is a cylindrical head, F, journaled in the standards B B, and to this head are fastened a series of slats, I I, which, when in a horizontal position, are supported upon a cross-bar, G, attached to the standards, and 40 also upon a bar, H, which is let into the legs E and under edges of the sides C. This bar H forms a gage for holding the sides the proper distance apart for mattresses of different width, it being notched at suitable points to fit on the 45 legs. Another gage, J, attached to the standards, holds the inner ends of the sides.

L represents a solid top hinged upon a removable rod, *h*, and provided at its outer end with a series of pins, *i*, upon which straps *m*, attached to the outer ends of the slats, are to 50 be fastened.

The operation of the machine is as follows: The door D is let down and the top L raised. The material of which the mattress is to be made is then laid on the slats I and spread in 55 proper form. The top L is then let down and pressed upon the material until the straps *m* can be fastened on the pins *i*. The ticking, having been previously sewed at the sides and one end, is now drawn over the top, material, 60 and slats, and the door D closed. The rod *h* is then drawn out and the top L drawn out at the back, the material and the slats yet remaining in the ticking. The mattress can then be tacked between the slats, if desired, and the 65 whole raised up, the head F turning on its journals, when the mattress can be easily drawn off and completed.

Some of the slats I are removable, so as to be taken out for making a mattress of less width, 70 in which case a narrower top is also used.

Having thus fully described my invention, what I claim as new, and desire to secure by Letters Patent, is—

1. The combination of the laterally-adjustable sides C C, legs E, hinged door D, and the gages H J, arranged to hold the sides C C at different points, substantially as and for the purposes herein set forth. 75

2. The journaled head F, with slats I, in combination with the hinged top L, having pins *i* and the straps *m*, substantially as and for the purposes herein set forth. 80

In testimony that I claim the foregoing I have hereunto set my hand this 27th day of 85 January, 1880.

CHARLES P. HOWE.
